UNITED STATES PATENT OFFICE.

JOHN BAKOS, OF NEWARK, NEW JERSEY.

AERONAUTICAL GARMENT.

1,254,110.

Specification of Letters Patent. Patented Jan. 22, 1918.

Application filed October 18, 1917. Serial No. 197,298.

To all whom it may concern:

Be it known that I, JOHN BAKOS, a subject of the King of Hungary, residing at Newark, in the county of Essex and State 5 of New Jersey, have invented certain new and useful Improvements in Aeronautical Garments, of which the following is a specification.

This invention relates to certain new and 10 useful improvements in aeronautical garments.

An object of the present invention is to provide a suit or garment for aeronauts which may be positioned on the body over 15 the usual wearing apparel to lie adjacent the body in its normal inoperative position, means being provided to cause a portion thereof to be removed to operative position to act as a parachute to lessen the fall of 20 the aeronaut should any part of the flying machine become broken to cause one to jump therefrom.

A further object of the invention is to provide a garment for aeronauts including 25 a body, bloomer and skirt sections, with means for normally holding the skirt section in position adjacent the bloomer and to further provide means for releasing the skirt section to cause the same to move outwardly to perform the usual function of a 30 parachute in decreasing the speed of the descent of the wearer.

With these general objects in view and others that will appear as the nature of the 35 invention is better understood, the same consists in the novel combination and arrangement of parts hereinafter fully described, illustrated in the accompanying drawings, and pointed out in the appended 40 claims.

In the drawings forming a part of this application and in which like designating characters refer to corresponding parts throughout the several views:—

45 Figure 1 is a perspective view of the garment with the skirt section distended to parachute position.

Fig. 2 is a front elevational view of a portion of the garment, with the skirt section and waist band shown in section.

50 Fig. 3 is a detail sectional view of a portion of the garment with one of the skirt distending ribs in operative position.

Fig. 4 is a detail plan view of a portion 55 of the garment illustrating the manner of retaining the skirt distending ribs in inoperative position, and,

Fig. 5 is a perspective view of one of the skirt ribs.

A large number of serious accidents are 60 caused by flying machines becoming inoperative or broken while in operation by inability of the aeronaut or driver of the machine being able to make his escape in a safe manner, which results in the death of 65 a large number of persons. The present invention therefore aims to provide a garment for aeronauts in which the garment may be worn over the usual wearing apparel and securely fixed to the body, the 70 same in no manner hindering the usual body movements and further being of such construction and weight as to be wholly unobjectionable in its use. Three principal parts constitute the garment, a body section, 75 bloomer section, and a skirt section, the skirt section being normally held in position adjacent the bloomer section when in inoperative position but to be distended to a substantially parachute form as indicated 80 by manually-controlled means, should occasion arise to compel the aeronaut to jump from the machine. The device is extremely simple in construction and operation, inexpensive to manufacture, and is believed to 85 be a material advance in the art to which it relates.

Referring more in detail to the accompanying drawings, the reference numeral 10 designates the body section of the garment, 90 11 the bloomer section, and 12 the skirt section, these parts being formed of any suitable material, such as water-proofed fabric or the like. The front of the body-section and skirt section is provided with 95 an opening 13 to permit the garment being positioned on the body, and this opening is closed by the lacing 14 while the front upper end of the bloomer section 11 is provided with the usual front opening 15 closed 100 by a lacing cord as shown in Fig. 1. That portion of the skirt section provided with the front opening is closed by a flap closure 16, the said flap and skirt 12 being provided with co-operating hooks and eyes 17. In 105 position on the body, the garment is caused to snugly engage the same by the lacing 14 and the closure flap 16. The lower ends of the bloomers 11 are securely fastened about the knees of the wearer by the buckle and 110 strap connections 18.

A waist-band section is positioned inwardly of the garment and constitutes the upper end of the bloomer section, the same

being shown more in detail on Sheet 2 of the drawings, and comprises the fabric strip 19 stitched to the upper end of the bloomers 11 as at 20 to provide a central passage-way or guide for a waist-band reinforcing ring 21 that may be formed of either bone or metal, the principal object of the same being to hold the waist-band in circular form about the body. The upper row of stitching 20 also constitutes the means by which the bloomers are secured to the skirt section.

The skirt section 12 is adapted to normally assume the position shown in Fig. 2 to lie adjacent the bloomers and be out of the way of the wearer and in no manner hinder his movements. To cause the skirt section to assume its position, I have provided the ribs shown in detail in Fig. 5 which consists of a shank portion 22 provided with an eye 23 at its outer end, by which the same is secured to the lower edge of the skirt section. The upper end of the shank 22 is bent to provide a spring coil 24, with the end 25 normally projected substantially parallel to the said shank 22 so that when the rib is attached to the garment in a manner to be described, the same will have a natural tendency to swing outwardly. To attach the rib to the garment, the rib shown in Fig. 5 is inverted and the extended end 25 projected through the opening 26 provided in the waist-band strip 19, so that the extended end will be in position between the upper end of the bloomers and the waist-band section 19 as clearly indicated on Sheet 2. The rib 22 is then swung outwardly and downwardly to the position shown in Figs. 2 and 3, against the tension of the coil 24 and to hold the same in position adjacent the bloomers, I have provided angle hooks 27 suitably positioned on the ribs 22 and adapted to be engaged by hinged rings 28 carried by the bloomer section. Reinforcing pads 29 are secured to the bloomers 11 in any preferred manner, as by stitching, and constitute the support for the hinged rings 28.

Means are provided to limit the outward movement of the descending ribs and consists of cords 30 secured at their ends to the skirt section 12 and the bloomers 11 by eyelets 31, the same being held taut when the skirt is distended to parachute position as shown in Fig. 3.

As before stated, the skirt is adapted to normally lie adjacent the bloomers and means are provided to cause the rib hooks 27 to be disengaged from the rings 28, the same consisting of a second ring 32 hinged to the lower ends of the reinforcing pads 29 and operating cords 33 passing through said rings at one end and continuing to be

connected to the ring 28. These operating cords pass through openings 34 suitably positioned about the lower end of the skirt section, and as shown, two of these cords terminate in a single extension 35, which passes through an eyelet 36 adjacent the waist line of the garment. It will be therefore seen that when the operating cord 33 is given a pull, the ring 28 will be moved from the position shown in Figs. 2 and 4 to the position shown in Fig. 3 to disengage the rib hook 27 therefrom, at which time the tension of the coil spring 24 will be permitted to assert itself and cause the ribs 22 to swing outwardly to the position shown in Fig. 3 and be limited by the reinforcing cords 30.

From the above detailed description of the device, it is believed that the operation and construction thereof is readily apparent, and while I have shown and described the preferred embodiments of the invention, I do not wish to confine myself thereto, as various forms, modifications and arrangements of the parts may be made without departing from the spirit and scope of the invention as claimed.

What I claim as new is:—

1. An aeronaut's garment comprising a body section, bloomer section and a skirt section, and coöperating means carried by the skirt section and bloomer section adapted to hold the skirt section in position adjacent the bloomer section, the said means carried by the skirt section when released from the means coöperating therewith adapted to distend the skirt section to parachute position.

2. An aeronaut's suit comprising a body section, a bloomer section, a skirt section, spring ribs connected to said bloomer and skirt section and adapted to normally force the skirt section outwardly, and coöperating means carried by the ribs and bloomers to hold the ribs and skirt section in inoperative position adjacent the bloomers.

3. An aeronaut's suit comprising a bloomer section and a skirt section, ribs carried by the bloomer and skirt section, each rib including a shank, the upper end of said shank being convoluted to form a spring, an extension carried by said spring adapted for securing the rib to the bloomer section, a hook carried intermediate the ends of the rib shank, a hinged ring carried by the bloomer section adapted to engage said hook to hold the same normally adjacent the bloomers, and manually-operable means for releasing the ring from the hook to permit the skirt section and ribs to be distended.

In testimony whereof I affix my signature.

JOHN BAKOS.
